(57) **CLAIM**

The ornamental design for a golf swing trainer, as shown and described.

DESCRIPTION

FIG. 1 is a lower front perspective view of a golf swing trainer;

FIG. 2 is an upper rear perspective view thereof;

FIG. 3 is a left side elevational view shown with broken line environment, the undisclosed right side elevation is a mirror image;

FIG. 4 is a bottom plan view thereof;

FIG. 5 is a bottom plan view shown with broken line environment;

FIG. 6 is a top plan view shown with broken line environment;

FIG. 7 is a front elevational view of FIG. 1;

FIG. 8 is a rear elevational view of FIG. 1;

FIG. 9 is a cross sectional view taken on line 9-9 of FIG. 3; and,

FIG. 10 is a reduced in scale, rotated left side elevational view shown with broken line environment.

The broken lines shown on FIGS. 3, 5, 6 and 10 depict environmental subject matter and form no part of the claimed design.

1 Claim, 6 Drawing Sheets
